UNITED STATES PATENT OFFICE

2,474,625

OPPOSED-ROLL CRUSHER WITH INTERLOCKING TEETH OF GRADUATED HEIGHTS

THERON G. GEROW, CHICAGO, ILL.

Application May 14, 1945, Serial No. 593,657

2 Claims. (Cl. 241—234)

1

This invention relates to an adjustable roll crusher having teeth continuously graduated in height from one end to the other.

Among the objects of my invention is to provide a roll crusher so constructed as to allow greater flexibility of roll adjustment, to produce an aggregate having mixed different sizes. My rollers have teeth varying in height with the largest teeth at one end graduating continuously to the smallest teeth at the opposite end. My rollers are adjustable so that the top size of the ground product may be accurately determined and produced with the further advantage that my rollers also produce varying smaller sizes along with the top size to provide an aggregate having mixed different sizes. This aggregate having mixed different sizes is of particular importance where the produce ground is coal, because it is often desirable in stokers and other devices that the coal be of varying sizes for maximum burning efficiency.

My invention also contemplates such other objects, advantages and capabilities as will later more fully appear and which are inherently possessed by my invention.

While I have shown in the accompanying drawings a preferred embodiment of my invention, yet it is to be understood that the same is susceptible of modification and change without departing from the spirit of my invention.

Referring to the drawings, Fig. 1 is a top plan view partly in section, of a roll crusher embodying my invention; Fig. 2 is a side elevational view partly in section with the hopper; Fig. 3 is a detailed sectional view of the breaker segments and diaphragm; Fig. 4 is an enlarged detailed sectional view of the breaker teeth; Fig. 5 is a detailed sectional view on line 5—5 of Fig. 1 and Fig. 6 is a detailed sectional view on line 6—6 of Fig. 1.

The embodiment selected to illustrate my invention comprises a main frame 10, on which are mounted two pairs of spaced bearing supports 11. Mounted on each of said supports 11, is a bearing 12. Extending between oppositely spaced bearings 12 are shafts 13 rotatably mounted thereon. Rotatably carried by each of the two shafts 13, is a roller 14.

Each of the shafts 13 is engaged at one end by a bevel gear 15. Said bevel gear 15, mesh with bevel pinions 16, which are connected to and moved by a drive shaft 17 connected to a suitable source of power.

Three of my four bearing supports 11, are slidably mounted on the frame and one is fixed

5 to the frame. The slidably mounted supports 11, each have a threaded bolt 18, a lock nut 19, a spring 20, and a spring nut 21 as shown in Figs. 1 and 2. This construction permits the rollers 14 to be moved to and from each other to a desired relative position. Bracket 27 is movable with adjacent bearing 12, while gear 16 is splined at 29 in longitudinally slidable position on shaft 17. Shaft 13 shown on the right in Fig. 1 may be adjusted. 10 Springs 20 are adapted to act as cushions, because bearings 12 are not too rigidly attached to supports 11. This permits the rollers 14 to spread apart slightly against springs 20, when a larger piece of coal passes through rollers 14. 15 In Fig. 5, as shown more in detail, spline 29 is set in shaft 17 and acts as a key to drive gear 16. In Fig. 6 as shown more in detail, bearing 12 is adjustably mounted on bracket 27, and bracket 27 is movable with bearing 12 against spring 20. 20 My rollers 14 are formed with a plurality of segments or staves 22, attached by bolts 27', extending through slots 28 to the diaphragm 23, the web 24, of which extends to hub 25 which engages the shaft 13. 25 Said rollers 14 are positioned opposite each other and are spaced relative to each other as desired by the slidable adjustment of said slidably mounted bearing supports 11. Said rollers 14 have interlocking teeth 26 graduated from the 30 highest at one end to the lowest at the other end, with the largest tooth of one roller opposite the largest tooth of the other roller, the smallest tooth of one roller opposite the smallest tooth of the other roller and the intermediate teeth of 35 graduate size of one roller opposite the intermediate teeth of corresponding size of the other roller, said rollers adapted to crush coal with said teeth to produce coal having some pieces of desired maximum size with other pieces of a smaller size to produce an aggregate having 40 mixed different sizes for maximum burning efficiency.

Having thus described my invention, I claim:

1. A roll crusher for coal comprising a frame, 45 two pairs of spaced bearing supports mounted on said frame with three of said supports slidably adjustable on said frame and the other of said supports fixed to said frame, bearings mounted on said supports, a pair of shafts rotatably 50 mounted on opposite bearings, a roller rotatably carried by each of said shafts, said rollers positioned opposite each other, and spaced relative to each other as desired, by the slidable adjustment of said slidably mounted bearing supports, 55 said rollers having interlocking teeth graduated

from the highest at one end to the lowest at the other end, with the largest tooth of one roller opposite the largest tooth of the other roller, the smallest tooth of one roller opposite the smallest tooth of the other roller and the intermediate teeth of graduate sizes of one roller opposite the intermediary teeth of corresponding sizes of the other roller, said rollers adapted to crush coal with said teeth to produce coal having some pieces of desired maximum size with other pieces of a smaller size to produce an aggregate having mixed different sizes for maximum burning efficiency.

2. A coal crushing device comprising a frame, two pairs of spaced bearing supports mounted on said frame, with three of said supports slidably adjustable on said frame, and the other of said supports fixed to said frame, means for holding said supports in desired adjusted position, bearings mounted on said supports, a pair of shafts rotatably mounted on opposite bearings, a roller rotatably carried by each of said shafts, said rollers positioned opposite each other, and spaced relative to each other as desired by the slidable adjustment of said slidably mounted supports, means for driving said shafts and moving the opposed rollers clockwise and counter-clockwise respectively, said rollers having interlocking teeth, said teeth on each roller being graduated from the highest on one end to the lowest on the other end, with the largest tooth of one roller opposite the largest tooth of the other roller, the smallest tooth of one roller opposite the smallest tooth of the other roller and the

5 intermediate teeth of graduate sizes of one roller opposite the intermediary teeth of corresponding sizes of the other roller, said spaced rollers adapted to receive coal dropped between them and said teeth adapted to crush said coal as it passes between the rollers to produce coal having some pieces of desired maximum size with other pieces of a smaller size to produce an aggregate having mixed different sizes for maximum burning efficiency.
